UNITED STATES PATENT OFFICE.

JAMES W. EVANS, OF DENVER, COLORADO, ASSIGNOR OF ONE-THIRD TO SAMSON BROTHERS, A FIRM COMPOSED OF CHARLES H. SAMSON AND FRED H. SAMSON.

ENGINE FOR COAL-BORING MACHINES.

1,181,126.

Specification of Letters Patent.

Patented May 2, 1916.

Application filed December 5, 1914. Serial No. 875,587.

To all whom it may concern:

Be it known that I, JAMES W. EVANS, a citizen of the United States, residing in the city and county of Denver and State of Colorado, have invented certain new and useful Improvements in Engines for Coal-Boring Machines; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in engines for coal-boring machines, my object being to provide a portable device of this character, which may be handled and operated by a single workman.

Having briefly outlined my improved construction, I will proceed to describe the same in detail, reference being made to the accompanying drawing, in which is illustrated an embodiment thereof.

Figure 1 is a top plan view of my improved machine showing the casing partly in horizontal section, whereby the cover is removed and the interior mechanism disclosed. Fig. 2 is a side elevation of the ma-

chine showing the same in use and on a smaller scale. Fig. 3 is a top plan view of the same, shown on the same scale. In Figs. 2 and 3, the coal bank is shown in section, cutting the hole which the auger enters.

Fig. 4 is a section taken on the line 4—4, Fig. 1, looking forwardly, or in the direction of the arrow adjacent said line, the parts being shown on a larger scale. Fig. 5 is a horizontal section taken on the line 5—5,

Fig. 4. Fig. 6 is a section taken through the endwise shiftable sleeve carried by the crank shaft, looking forwardly, the said shaft being shown in elevation.

The same reference characters indicate the same parts in all the views.

Let the numeral 5 designate a casing having a closed bottom 6, side walls 7, a front wall 4 and a rear wall 3, the latter being hollowed out as best illustrated in Figs. 1 and 3, to approximately fit the body of the user, whereby the latter is enabled to press forwardly upon the machine and thus feed the auger into the coal. Within the casing

are located two partitions 10, which are spaced sufficiently from the side walls 7 to make room for oscillating cylinders 8, the pistons of which are connected by means of rods 9 with end cranks 12 of a shaft 13 which is journaled in bearings 14 formed integral with the partitions 10 of the casing. Splined on this shaft and endwise movable thereon, is a sleeve 15 carrying beveled gears 16 at its opposite extremities and suitably spaced to alternately mesh with a relatively large gear 17 made fast on an operating shaft 18, which is journaled in the casing as shown at 19 and 20. This shaft protrudes forwardly from the casing and to its opposite extremity is attached an auger 21.

The motive fluid for actuating the pistons of the cylinders 8 is delivered by a main conduit 22, to a pipe 23, the latter being securely mounted in the casing of the machine, its opposite extremities communicating with fluid chests 24 which are arranged in operative relation with the cylinders 8 to supply the latter with motive fluid for actuating the pistons (not shown) for the purpose of imparting the rotary movement to the crank shaft 13 through the medium of the piston rods 9 and the cranks 12.

Within the portion 25 of the conduit 22, within the casing, is located a valve 26 which, when properly adjusted within its casing 28, causes a passage 27 of the valve to register with a passage 29 of the valve casing, said passage communicating with the conduit on opposite sides of the valve casing. This valve is controlled from a rotary bar 29 whose opposite ends are journaled in boxes or bearings 30 and 31, formed integral with the frame work of the casing. Connected with a crank 32 fast on this bar, is a rod 33, whose extremity remote from the bar is connected as shown at 34, with a crank arm 35 fast on the stem 36 of the valve 26. By imparting a partial rotary movement to the bar 29, the operator may actuate the valve 26 to cut off the motive fluid, or turn it on as may be desired. In order to supply the pistons of the cylinders 8 with the necessary lubricant, I employ an oil cup 37 which communicates by a bottom opening 38, with a short conduit 39 which is threaded into the valve casing 28 as shown.

at 40. This casing is provided with an opening 41 into which the conduit 39 is threaded. This opening extends to the conical opening 42 of the valve casing, in 5 which the valve 26 is located. When this valve is adjusted (see Fig. 5), to allow the motive fluid to pass to the cylinders, the opening 41 is closed and the flow of oil to the passage 27 cut off. However, as soon as 10 the valve is shifted to cut off the motive fluid or so that the passage 27 is out of register with the opening 43 of the valve, and the last named opening brought into register with the opening 41, the valve-opening 43 will be filled with oil. Hence, 15 as soon as the valve is adjusted to allow the motive fluid to pass to the cylinders, a quantity of oil equal to that contained in the valve opening 43 is brought into alignment 20 with the passage through the conduit, and is consequently carried by the motive fluid into the cylinders.

When drilling coal, it very frequently becomes necessary, owing to the sticking of the auger in the bank of coal, to reverse the movement of the auger and for this reason, provision is made for readily reversing the movement of the operating shaft 18. For instance, when the left hand pinion 16 is in 25 mesh with the relatively large gear 17, it may be assumed that the auger is operating in the direction to travel into the coal. Now, if it becomes necessary to reverse this movement, the sleeve 15 must be shifted on the 30 crank shaft 13, to bring the right hand pinion 16 into mesh with the larger gear 17. This is accomplished by imparting a partial rotary movement to a hand bar 44, which is connected by means of a link 45, with an 35 endwise movable shaft 46, which is slidable in openings formed in the partitions 10. Secured to the shaft 46 is a bracket 47, whose forward extremity is made fast to a flat ring 48, loose on the sleeve 15, but located between two shoulders 49 and 50 which 40 abut against the opposite ends of the ring. The bar 44 is journaled at its opposite ends in bearings 70 and 71, which are carried by the framework of the machine. From this, 45 it will be understood that when the operator wishes to shift the sleeve 15 on the crank shaft to impart the reverse movement to the operating shaft 18, it will only be necessary to impart a partial rotation to the bar 44 in the proper direction, to shift the left-hand pinion 16 out of engagement with the gear 17, and bring the right-hand pinion 50 into engagement with the said gear, or vice versa, as may be required.

Attention is called to the fact that the cylinders 8 are of the usual oscillatory character, and that, by virtue of this oscillation, the fluid for operating the pistons is admitted to the cylinders at properly timed intervals, each of the cylinders being mounted

to turn on a single trunnion 52, its flat side 53 being held in operative engagement with the side of the partition 10 adjacent the fluid chest 24, by means of a spiral spring 73, one extremity of which bears against the chest 24 while the other extremity engages a stop nut 54 fast on the inner extremity of the trunnion.

In order to lock the rotary bar 44 in the desired position of adjustment after shifting the sleeve 15 for the purpose of bringing either pinion 16 into operative engagement with the large gear 17, I employ a spring-actuated pin 55 which is slidable in lugs 56 and 57, formed on the bar, a helical spring 58 being located between the lug 57 and the stop 59 on the pin. The forward extremity of this pin is adapted to enter recesses 60 formed in the adjacent stationary bearing 70. When it is desired to unlock the bar 44 for purposes of rotating the same in its end bearings, the pin 55 is moved rearwardly against its spring 58 far enough to disengage its forward extremity from the corresponding recess 60. As soon as the bar is 80 adjusted, the pin 55 will be brought into register with another recess which the pin 85 will enter as soon as released.

To aid the operator in supporting the machine, a strap 61 is employed, the extremities of this strap are connected with leather loops 62, which are applied to the front wall 4 of the casing. This strap passes over the shoulders of the operator. During operation, the machine is supported by the user 95 by means of this strap and the rotary hand-bars 29 and 44 which are grasped by the operator, and are rotated at will for the purpose of lubrication and turning the motive fluid on or off, or for the purpose of reversing 100 the motion of the auger, as may be required.

Assuming that the operator has the machine in position for work, he places the auger against the bank of coal, presses his body against the rear wall 3 of the casing, and turns on the motive fluid by imparting a partial rotary movement to the bar 29. In this event, the auger begins to rotate, and during this operation, the user feeds the 110 auger into the coal by pressing with his body upon the rear wall of the casing. If the auger should become stuck, or if for any reason it should become necessary to reverse 115 its travel, a partial rotary movement will be imparted to the bar 44, as heretofore explained.

Attention is called to the fact that when the machine is not in use, the auger may be detached and the apparatus swung around 120 on the body of the operator in such a manner that it is supported by the strap 61, the body of the machine being brought into position under one arm with the front hollowed-out wall 3 uppermost, whereby the 130

machine will fit under the arm of the user and may be easily transported from place to place.

Having thus described my invention, what I claim is,—

1. A portable boring machine, comprising a casing, operating mechanism inclosed thereby, means connected with said casing for supporting the machine upon the body 10 of the operator, and exteriorly located hand bars journaled in the casing and connected in operative relation with the mechanism within the casing, for controlling the same.

2. A portable boring machine comprising 15 a casing, operating mechanism located therein, a tool with which said mechanism is operatively connected, an exteriorly located hand bar journaled in the casing, and an operative connection between said hand bar 20 and the mechanism within the casing, for controlling the same.

3. A portable boring machine comprising 25 a casing, a crank shaft journaled therein, an operating shaft carrying a tool, a gearing connection between the two shafts including a member shiftable on the crank shaft for

reversing the rotation of the operating shaft, a hand bar journaled in the casing and an operative connection between said hand bar and the reversing member, substantially as 30 described.

4. A portable boring machine comprising a casing, a tool shaft journaled therein, operating mechanism also carried by the casing and connected in operative relation with 35 said shaft, means connected with the forward extremity of the machine to aid in supporting the same upon the body of the operator, the rear portion of the casing being hollowed out to approximately fit the body 40 of the operator, and hand bars exposed on opposite sides of the casing and connected in operative relation with the operating mechanism for controlling the same, substantially as described.

In testimony whereof I affix my signature in presence of two witnesses.

JAMES W. EVANS.
